UNITED STATES PATENT OFFICE.

DAVID FOX AND LOUIS ROSENBAUM, OF NEW YORK, N. Y.

CAP.

SPECIFICATION forming part of Letters Patent No. 242,292, dated May 31, 1881.

Application filed April 26, 1881. (No model.)

To all whom it may concern:

Be it known that we, DAVID FOX and LOUIS ROSENBAUM, of the city, county, and State of New York, have invented a new and Improved 5 Cap; and we do hereby declare that the following is a full, clear, and exact description of the same, reference being had to the accompanying drawings, making part of this specification.

10 This invention is in the nature of an improvement in caps; and the invention consists in a cap with the back of the cover thereof extending in one piece below the lower edge of the cap-body, where it is stitched, to the 15 edge of which extension of the cover is fastened, midway of its width, a band which encircles the cap, and its two ends united and fastened to the front of the cap, substantially 20 as is hereinafter described.

25 In the accompanying sheet of drawings, Figure 1 is a rear view, partly in section, of our cap with band pulled down to protect the ears and neck; Fig. 2, a side view, partly in section, of our cap with band pulled up and encircling cap-body, and Fig. 3 a part longitudinal section of cap with band pulled down.

Similar letters of reference indicate like parts in the several figures.

This invention relates particularly to caps 30 to be worn in cold and inclement weather, and belongs to that class known as "band-caps," or caps provided with a device that can be drawn down and around the ears and neck of the wearer. This class of caps being old and 35 well known, no particular description need be given of their general construction. They all have some features in common, and the invention hereinafter described pertains to improvements on such features.

40 The body A of our cap is constructed in the usual manner of any suitable material, and this body is covered with cloth or other material, which is technically known as the "cap-cover" A'. In caps this cover usually extends no further than the lower edge, a, of the body of the 45 cap; but in our invention the rear part of this cover extends continuously below this lower edge, a, forming a cape, B. This cape is fastened to the lower edge of the cap-body, as at c.

50 To the lower edge, d, of this cape or extension B of the cover is sewed or bound a protector or band, C. This band or protector is fastened

to this cape or extension B in a line, e, that is midway, or substantially midway, between the upper and lower edges, f and g, of the band, 55 leaving these edges unconfined. This band extends on both sides from the place where it is fastened to the cape or extension toward the front of the cap, where its ends meet and are united by a button, or by any desirable means. 60

The cap, in this way provided with its protector and constructed substantially as described, is operated by pulling down the band C when it is desired to protect the ears and neck of the wearer, in which case the band is 65 in the position shown in Figs. 1 and 3, and at other times the band is drawn up by merely pulling its edge upward, when the cape or extension B will readily fold at the place e, at which it is attached to the body, permitting 70 the band C to be raised and encircle the body of the cap, as shown in Fig. 2, the folded portion of this cape or extension B in this position lying snugly up against the cap and between it and the band C, and the unconfined edges f 75 and g of the band readily and smoothly accommodating themselves to the shape of the cap without fold, presenting a neat appearance, and kept sufficiently snug around the cap, when in its upper position, to prevent its 80 falling down until intended for use, as before described.

Having thus described our invention, what we claim as new, and desire to secure by Letters Patent, is—

1. A cap with the back part of its cover extending continuously below the lower edge of the cap, at which lower edge it is fastened to the cap-body, and provided with a band secured at the middle of its width to the lower 90 edge of said extension of the cover, substantially as and for the purpose described.

2. In a cap with the rear part of its cover extending below the lower edge of the cap-body, a protector sewed to said extension at the middle, e, of its width and extending to the front of the cap, at which point the ends of the protector are united and secured to the cap, substantially as and for the purpose described.

DAVID FOX.
L. ROSENBAUM.
